ISRAEL J. JOHNSON, OF REDDING, CALIFORNIA.

ROTARY PUMP.

1,074,326.

Specification of Letters Patent. Patented Sept. 30, 1913.

Application filed February 3, 1913. Serial No. 745,959.

To all whom it may concern:

Be it known that I, ISRAEL J. JOHNSON, a citizen of the United States, residing at Redding, in the county of Shasta and State of California, have invented new and useful Improvements in Rotary Pumps, of which the following is a specification.

This invention relates to a rotary pump.

It is the object of this invention to provide a rotary pump of the type in which a revolvable drum carrying blades is mounted eccentrically in a cylinder casing having inlet and outlet ports.

The principal object of this invention is to provide means for obviating rubbing contact between the blades and casing, and to provide means for preventing noise caused by the blades passing over the division between the intake and discharge openings of the casing.

A further object is to provide a rotary pump which is simple in construction and positive in its action.

Further objects will appear hereinafter. The invention primarily resides in a drum revolvably mounted in the cylinder of the casing, eccentric thereto, a series of divided blades or vanes extending diametrically through the drum with spring members bearing between the divisions of the blades, rollers adjacent the outer ends of the blades, and a track or runway in the casing on which the rollers travel to furnish a rolling contact between the blades and the casing.

The invention further consists of the parts and the construction and combination of parts as hereinafter more fully described and claimed, having reference to the accompanying drawings, in which—

Figure 1 is a vertical longitudinal section of the invention taken on the line X—X of Fig. 2. Fig. 2 is a transverse section on the line Y—Y of Fig. 1, partly in elevation. Fig. 3 is a detail elevational view of the drum with parts broken away.

In the drawings A represents the pump casing which is formed with a cylindrical interior which communicates with an intake opening 2 and a discharge opening 3 through segmental channels or passages 4, formed in the casing A. The intake and discharge openings 2 and 3 are separated by

means of a wall or partition 5 which terminates at its inner end adjacent the cylindrical interior of the casing. The segmental 55 channels 4 leading from the intake and discharge openings 2 and 3 extend approximately three-fourths around the cylindrical interior of the casing A, as shown in Fig. 1.

Mounted in suitable bearings 6 carried in hubs 7 formed on the casing A, is a shaft 8 which extends through the cylindrical interior of the casing A, eccentric to the axis thereof. Rigidly mounted on the shaft 8 within the casing A, is a hollow drum or 65 cylinder 9, which is formed of quadrants secured together by means of face plates 10, as shown in Fig. 3, which face plates are bolted to the end faces of the quadrants. The cylinder or drum 9 is of such diameter that 70 its outer periphery will be in sliding contact with the inner wall of the casing A at a point adjacent to the inner end of the partition 5. The quadrants forming the cylinder 9 are spaced a short distance apart to 75 form diametrically opposed slots 11 extending transversely of the perimeter of the drum, the full width thereof. Mounted in the drum, and extending through the slots 11 is a pair of blades or vanes, each of which 80 is formed of two connected parts 12 and 12'. The blades 12—12' are of such length that their outer ends will almost contact the surface of the cylindrical interior of the casing A, as shown in Fig. 1, and the portions 12 85 of the blades are bent outwardly at 12^a to pass alongside of the shaft 8.

The connection between the portions 12 and 12' of the blades consists of a tongue 13 formed on the portion 12', which extends 90 into a slot or groove 14 formed on the portion 12. The tongue 13 and the slot 14 extend the full width of the blades.

Mounted within the portions 12 of the blades, in recesses formed in the slotted ends 95 thereof, are helical expansile springs 15, which bear between shoulders on the portions 12 of the blades and the inner ends of notches formed in the tongues 13 on the portions 12' of the blade, in such manner as 100 to normally retain the ends of the blades in their outermost position. A sufficient space is provided between the connected ends of the blade portions 12 and 12' to allow them

to have a slight movement toward each other when the blades contact and ride over the end of the partition 5, as will be later described.

5 The outer ends of the blades 12-12' are cut away on their end edges to form offsets, in which rollers 16 are mounted; the rollers 16 being revoluble upon bushings 17 carried by studs 18 formed on the edges of the 10 blades 12-12', as shown in Fig. 2. The outer faces of the rollers 16 slidably contact the end blades of the casing A. The peripheries of the roller 16 extend a short distance beyond the ends of the blades 12-12' 15 and are adapted to travel upon the peripheral walls of the cylindrical chamber in the casing A; the walls of the cylinder thus forming a runway or track for the rollers.

Formed in the drum 9 at the ends of the 20 slots 14, are recesses 19 into which the rollers 16 pass when the outer ends of the blades 12-12' are disposed in their innermost position in relation to the drum 9. A substantial, durable construction is obtained by extending the blades 12-12' 25 through the drum and forming them with offset portions 12^a to clear the shaft 8. The shaft 8 may thus extend entirely through the drum 9 and be supported in the bearings 6 on each side of the drum; the portions 12^a of the blades being cut away so that the blades may cross each other at right angles, as shown in Fig. 1.

In the operation of the invention, the shaft 35 8 is rotated by means of any suitable source of power, to rotate the drum 9 within the casing A. The rotation of the drum 9 causes the blades 12-12^a to rotate therewith; the rollers 16 on the outer ends of 40 the blades traveling on the inner wall of the cylindrical chamber formed in the casing A, and acting to hold the ends of the blades 12-12' out of contact with the casing A, and at the same time form a rolling bearing for the end thrust of the blades, due to centrifugal force. The blades 12-12^a 45 in rotating with the drum 9 are caused to have a reciprocal movement in relation to the latter, and are thus caused to ride 50 back and forth in the slots 11. When the ends of the blades in moving around with the drum 9, strike the partition 5, they are slightly compressed lengthwise in opposition to the springs 15, thus silencing the impact 55 of the blades on the partition 5. The blades in rotating, act to draw liquid into the pump through the intake opening 2 in the manner common in rotary pumps, and advance it around the interior of the casing A and discharge it through the discharge opening 3.

It is manifest that the pump may be driven in either direction to discharge through either of the ports 2 or 3. By ex-

tending the channels 4 to open into the 65 crescent-shaped space between the drum 9 and the casing A at a point where the decrease of the sectional area of the space is slight, the full working capacity of the 70 blades is obtained, both in drawing the liquid into the pump casing and discharging it therefrom.

Having thus described my invention, what I claim and desire to secure by Letters Patent, is—

75 1. In a rotary pump, a casing having its interior periphery formed on arcs of different radii, parallel contiguous inlet and discharge passages in the larger periphery, with a dividing septum, a drum having an axis intermediate of the axes of the casing, pistons extending through radial channels in the drum, and guides coincident with the smaller arc of the casing, whereby the pistons are held in operative contact with said 85 smaller arc of the casing opposite the inlet and discharge and are carried free from the remainder of the casing during rotation.

2. A rotary pump having parallel, contiguous inlet and discharge passages at one 90 side of the periphery, with an intermediate septum, a channeled crescent-shaped interior portion, the side walls of which have the same radius with the smaller arc of the casing which is located opposite to the inlet 95 and discharge passages, a sectional hollow drum revoluble within the casing, having its axis intermediate of the axes of the casing, and pistons slideable in slots at right angles through the drum, said pistons having rollers 100 journaled in their ends and adapted to travel on the side walls of the crescent and maintain operative contact between the outer edges of the pistons and the smaller casing surface.

105 3. A casing for rotary pumps having its interior periphery formed of cylindrical arcs of different radii, parallel contiguous inlet and outlet passages connecting with the larger arc, a rotary piston carrying drum journaled 110 within the casing and having an axis different from those of the casing, pistons slideable radially through the drum, and a crescent-shaped guide therefor within the casing having its thicker portion coinciding 115 with the larger arc of the casing and its interior curvature of the same radius and continuous with the smaller arc of the casing.

4. In a rotary pump of the character described, a casing with its interior periphery in arcs of different radii, crescent-shaped guides, the curvature and the terminating horns of which are continuous with the smaller arc of the casing, parallel, contiguous inlet and outlet passages through the opposite periphery of the casing, a drum 125 within the casing having a continuous shaft

journalized outside of the casing ends, and | my hand in the presence of two subscribing
pistons slideable at right angles through the | witnesses.
drum by the action of the guides, said pis-
tons being curved in the center to clear the
5 shaft, and one of them slotted to clear each
other.

In testimony whereof I have hereunto set

ISRAEL J. JOHNSON.
